UNITED STATES PATENT OFFICE.

WILLIAM V. ELLIOTT, OF LIMA, OHIO, ASSIGNOR OF ONE-HALF TO GEORGE HALL, OF SAME PLACE.

WATER-HEATER FOR FIRE-ENGINES.

SPECIFICATION forming part of Letters Patent No. 279,085, dated June 5, 1883.

Application filed February 19, 1883. (No model.)

To all whom it may concern:

Be it known that I, WILLIAM V. ELLIOTT, a citizen of the United States, residing at Lima, in the county of Allen and State of Ohio, have 5 invented certain new and useful Improvements in Water-Heaters for Fire-Engines, of which the following is a specification, reference being had therein to the accompanying drawings.

10 My present invention relates to certain improvements in water-heaters, and has for its object to provide means of improved construction, whereby the water in boilers—such, for instance, as the boilers of steam fire-engines— 15 may be kept heated to a degree near the boiling-point, so that when steam is wanted it may, by the application of more heat, be speedily made.

After describing the construction of the 20 parts the invention will be designated in the claims.

In the drawings hereto annexed, Figure 1 is a vertical section of the water-heater. Fig. 2 is a side view of the water-heater and boiler, (broken.) Fig. 3 is a top view of the burner and bottom of the water-heating chamber. Fig. 4 is a top view of the burner alone. Fig. 5 is a cross-section on $x-x$. Fig. 6 is a cross-section on $z-z$.

30 The letter A designates an upright tube or cylinder having its lower end, A', enlarged. Within this tube is a somewhat smaller tube, B, also enlarged at its lower end. A space, e, is thus left between the two, which in practice 35 may constitute simply an air-space, or which may be filled with asbestos or other packing, for the purpose of preventing loss of heat by radiation. The interior tube, B, constitutes a flue, B', for hot air and the ascending products of combustion from the burner D below.

The water from the boiler enters the heater by a pipe, E, and is heated primarily at the burner, as hereinafter described, and thence passes into and through a number of short 45 vertical pipes, F, which are arranged in two circles, as shown in Fig. 3. These circles of vertical pipes occupy the chamber formed by the enlargement A'. The upper ends of the two circles of pipes are connected by a ring-shaped head or conductor, F', from which a

series of pipes, F², extend up through the hot-air flue B'. In the present instance five of these pipes are shown; but the number may vary from this, and they may extend straight or spirally. The upper ends of these are joined 55 into a head or conductor, F³, from which an outlet-pipe, G, extends laterally, passing through the side of the tubes A and B into the boiler H. By this construction and arrangement of pipes in the chamber and hot-air flue, 60 the water passing through them is first subjected to heat at the burner, and from there, in its passage all the way to the outlet-pipe G, it is constantly subjected to heat.

The burner D is of special construction, and 65 is contrived with particular reference to its adaptability for heating water. It may be employed in connection with a water-heater wherein the pipes are differently arranged than as here shown. This burner may be employed to burn ordinary gas, or it may generate and burn the vapor of gasoline, as desired. The parts connected with the burner are the annular water-receiving chamber e, having a central vertical air and gas passage, 70 f. The pipe E from the boiler lets the water into this receiving-chamber. An annular head, g, has a number of orifices, g', for the escape of gas. From each of these orifices a jet of flame projects when the burner is lighted. The 75 central air and gas passage, f, and the annular head g are connected by passages h. A water-heating chamber, i, above the burner has a convex rounded bottom, i', which sets down into the annular burner-head g; thereby the 80 jets of flame issuing from the orifices g' entirely surround and play against the said water-chamber i. The annular water-receiving chamber e below the burner and the water-chamber i above the burner are connected 85 by ducts k, which pass under the burner-head g. The upper or neck part of the water-chamber i connects with the base F⁴, to which the circles of the vertical pipes F are attached. A small tube, N, conveys the gas to the burner, 90 and has a gas outlet or aperture, p, which is controlled by a valve or cock, q. The said outlet-aperture is directly below the central passage, f. It will be seen that when the burner is warm, gas issuing from the aperture 95 100

will be mingled with air in the central passage, *f*, on the principle of the Bunsen burner, and both air and gas will pass up and through the passages *h* to the annular burner-head *g*, 5 where the jets of flame, being of the non-luminous character, create an intense heat. While the burner operates as just described, the water entering by pipe *E* surrounds the lower part of the burner, and from thence 10 passes through the ducts *k* into the water-heating chamber *i*, and thence into the pipes *F*. This construction of burner and water-chambers and passages serves to utilize the largest possible proportion of the heat in heating 15 the water. The hot air produced by the jets of flame passes first up and around the pipes *F*, and then up the flue *B'*, there surrounding the pipes *F'*. A damper, *r*, at the top of the flue regulates the draft. A blow-off or 20 cleansing pipe, *s*, is connected to the annular water-chamber *e*, and is closed by a cock, *t*.

From what has already been stated the operation 25 of the apparatus will be obvious. The water from the boiler enters the heater by the pipe *E*, and is subjected to the direct heat of the burner, and then to the heat of the hot-air flue, and finally passes out of the heater by the lateral pipe *G* and into the top of the boiler. A circulation of the water is thus 30 maintained.

Having described my invention, I claim and desire to secure by Letters Patent of the United States—

1. A water-heater constructed as herein described—that is to say, an upright hot-air flue, *B'*, having an enlarged lower end, *A'*, which incloses a number of short vertical water-pipes, *F*, arranged in circles, the lower ends of the said short pipes connecting with a base, *F'*, provided with an inlet-pipe, and the upper ends with a ring-shaped head, *F'*, from which a series of pipes, *F''*, extend up through the hot-air flue to a head or conductor, *F'''*, provided with a lateral outlet-pipe, *G*, as set forth. 35

2. In a water-heater, the combination of a 40 burner secured to the lower end of the water-heater apparatus, an inlet or water-receiving chamber immediately below the burner, and ducts to convey the water from the latter to the heater apparatus above, as set forth. 45

3. A burner having a vertical gas and air passage, *f*, an annular head, *g*, provided with gas-escape orifices *g'*, and passages *h*, connecting the vertical passage and the annular head, in combination with a water-receiving chamber, *e*, below the burner, a water-heating chamber above the burner, having its bottom adapted to set down into the annular head, and ducts to convey the water from the receiving-chamber to the heating-chamber, as set forth. 50

In testimony whereof I affix my signature in presence of two witnesses.

WILLIAM V. ELLIOTT.
